DESIGN FOR A PIANO BENCH

William Zaiser, Rockville Centre, N. Y., assignor to
The Rudolph Wurlitzer Company, Cincinnati,
Ohio, a corporation

Application December 10, 1938, Serial No. 81,703

Term of patent 7 years

To the Commissioner of Patents:

Be it known that I, William Zaiser, a citizen of the United States, residing at Rockville Centre, in the county of Nassau and State of New York, have invented a new, original, and ornamental Design for a Piano Bench, of which the following is a specification, reference being had to the accompanying drawing, forming part thereof.

In the drawing, Fig. 1 is a front perspective view of a piano bench, showing my new design; and Fig. 2 is a top plan view thereof.

The undisclosed rear wall of the piano bench is plain, and the undisclosed end wall is of the same appearance as the end wall shown.

I claim:

The ornamental design for a piano bench, as shown and described.

WILLIAM ZAISER.
